UNITED STATES PATENT OFFICE.

HERMANN VON DER HEYDT, OF CHICAGO, ILLINOIS.

SELF-WINDING WATCH.

SPECIFICATION forming part of Letters Patent No. 332,023, dated December 8, 1885.

Application filed December 17, 1884. Serial No. 150,550. (No model.)

To all whom it may concern:

Be it known that I, HERMANN VON DER HEYDT, of Chicago, in the county of Cook and State of Illinois, have invented certain new and useful Improvements in Self-Winding Watches; and I do hereby declare that the following is a full, clear, and exact description thereof, reference being had to the accompanying drawings, and to the letters of reference so marked thereon, which form a part of this specification.

The object of this invention is to provide an improved construction in self-winding watches of that class in which the mainspring is wound by means of the vibrations of a pendulum put in motion by the movements of the wearer in walking or under other circumstances.

The self-winding devices herein illustrated as embodying my invention are, in their general features of construction, similar to those heretofore used and first known as the invention of Breuget, of Paris, France, and to those illustrated in Letters Patent of the United States No. 211,280, granted upon the 7th day of January, 1879, to August Von Loehr, of Vienna, Austria, and in Letters Patent of the United States granted to me upon the 19th day of February, 1884, and numbered 293,691.

The winding device herein shown and above referred to consists, essentially, of a weight or pendulum which is pivotally connected with the plate of the watch, an arbor mounted concentrically with the pivotal axis of the pendulum, and provided with a ratchet-wheel, a click or pawl upon the pendulum-arm, engaged with the ratchet-wheel in such manner as to turn the latter when the pendulum is vibrated, a detent also engaged with the ratchet-wheel and constructed to prevent backward rotation of the latter, a spring opposing the weight of the pendulum so as to hold the latter normally about midway between the upper and lower limits of its movement and adapted to yield, so as to permit a vibratory movement of the pendulum when the latter is shaken by the movements of the body, and a train of gears connecting the arbors of the said ratchet-wheel with the mainspring-arbor of the watch.

The important feature of novelty in the device herein shown and illustrated consists in

an improved stop device, by means of which the overwinding of the watch will be prevented, and the pendulum will at the same time become locked or held from further vibration when the watch is wound to a desired degree, and will be held immovable until the watch is run down or the spring unwinds to a definite extent, when said pendulum will be released and permitted to again operate in winding the watch.

In the self-winding devices shown in the patent to Von Loehr, referred to, which, with the exception of my prior patent, embodies the most recent improvements in devices of this character, no stop mechanism is used; but the vibratory pendulum is made relatively light, and a spring-pawl upon the weight-arm, which pawl engages the ratchet-wheel, is made to yield backwardly upon any considerable resistance to the rotation of the ratchet-wheel over that ordinarily required for winding the watch, so that when the watch has been wound the said pawl will yield to permit the continued vibrations of the pendulum, but will not put too great a strain upon the mainspring. This construction is objectionable for several reasons, the principal of which is that the weight or pendulum being relatively light, it is necessary, in order to get the required power, to gear the ratchet-wheel with the spring-arbor in such manner that a great many vibrations of the pendulum are necessary to wind the watch, it being stated in Von Loehr's specification that about twelve thousand vibrations of the pendulum may be necessary for completely winding the watch. This number of vibrations is greater than will ordinarily occur in case the wearer takes no more than the ordinary amount of exercise, so that a watch constructed in this manner will obviously be liable to run down.

In the watch shown in the patent granted to me, and above referred to, a device is shown constructed to prevent overwinding, and which is also adapted to arrest the movement of the pendulum. Such device, although useful so far as the prevention of overwinding is concerned, is found defective for the purpose of holding the pendulum from movement after the watch is fully wound up, for the reason that in it there is no especial means provided for causing the engagement of the stop device

with the pendulum for a definite length of time. On the contrary, the stop device for arresting the pendulum is caused to engage the pendulum by the vibrating movements of the pendulum itself, so that as soon as the spring begins to unwind or the watch to run down from its completely-wound condition the locking device immediately becomes released. The effect resulting from this construction is that when the person carrying the watch continues to move after it has been wound up, the weight or pendulum will continue to become engaged with and disengaged from the locking devices at short intervals, thus causing an almost constant action of the stop device under such circumstances, calculated to injure and rapidly wear out the same.

To obviate the objections to stop devices heretofore used that have been above pointed out, I employ, in connection with a winding mechanism and a detent constructed to engage the pendulum or weight, intermediate devices consisting, essentially, of a spring or its equivalent adapted to throw the detent into engagement with the weight or pendulum, and mechanism adapted to hold said detent out of engagement with the pendulum under ordinary circumstances, or when the watch is being wound, which mechanism is so constructed that the said detent will be released at the moment the watch is completely wound up. The devices for holding the detent out of engagement with the weight are so constructed, also, that they will not permit the disengagement of the detent from the pendulum until a certain definite period after the watch is fully wound, so that the mainspring may be allowed to run down a certain length of time before the weight is released and the winding begins again. By this means the continued engagement and release of the pendulum or weight and the consequent continued operation of the stop device (which is objectionable for reasons before stated) are prevented.

Another feature of novelty in the winding mechanism herein illustrated consists in a device for releasing both the pawl upon the weight-arm and the stationary detent engaged with the ratchet, whereby the watch may be unwound when it is desired to take the watch apart for repairs or other purposes, as will be hereinafter described.

The invention may be more readily understood by reference to the accompanying drawings, in which—

Figure 1 is a plan view of the watch with the dial removed, illustrating the parts by which the self-winding is effected. Fig. 2 is a similar plan with the plate adjacent to the dial removed, showing only the parts of the watch relating to the stop mechanism. Fig. 3 is a detail view illustrating the operative parts of the stop mechanism shown in Fig. 2 in a changed position. Fig. 4 is a section through the mainspring-barrel, taken upon the line $\times \times$ of Fig. 2. Fig. 5 is a detail perspective view of the outer end of the spring

shown in Fig. 4. Fig. 6 is a detail illustrating a modified form of the device shown in Figs. 2, 3, and 4. Fig. 7 is a view similar to Fig. 70 2, showing a modified form of the stop device. Fig. 8 is a detail view showing the parts illustrated in Fig. 7 in a changed position. Fig. 9 is a detail sectional view taken upon line $\times \times$ of Fig. 7. Fig. 10 shows another modified 75 form of the device. Fig. 11 is a detail section taken upon line $\times \times$ of Fig. 1. Fig. 12 is a detail elevation of the parts shown in Fig. 11.

In the drawings, A is a pendulum or weight, (clearly shown in Figs. 2 and 7,) which is secured to a rod or pendulum-arm, A', said arm being pivoted to the plates P and P' of the watch, as herein shown, by means of an arbor, A², having bearings in the said plates, to which arbor the said arm is rigidly connected. 85

B is a ratchet-wheel, which is mounted concentrically with the pivotal axis of the arm A', a construction being preferably used for this purpose in which the said wheel is attached to a sleeve mounted to rotate freely on 90 said arbor.

C is a lifting-spring, which opposes the weight of the pendulum, and which is adapted to act upon the arm A' in such manner as to hold the weight at a point approximately 95 midway between the upper and lower limits of its movement when the wearer is at rest, said weight being adjusted in strength to correspond with the weight of the pendulum, so that the latter may be readily moved, 100 and will thereby be caused to vibrate by the motion of the wearer in walking or otherwise. The lifting-spring C may be of any form found desirable and applied in any manner, so that it will properly oppose the 105 weight of the pendulum. As herein shown, however, the said spring is in the form of an ordinary curved leaf spring, which rests at its free end against the side of the arm A', and is secured at its opposite end by a screw, 110 c, to the plate P adjacent to the dial of the watch. In the particular form of the device shown the spring C is provided with a solid part or shank adjacent to the screw c, in which is inserted a set-screw, c', the head of which is 115 adapted to bear against a raised part of the said plate P, whereby the position of the free end of the spring with reference to the arm A' may be adjusted in putting the parts together or afterward, as required. The arm A' is 120 preferably located within the recess formed in the plate P beneath the dial to afford space for the pinions by which the proper relative speed is given to the hour and minute hands, the said pendulum-arm being curved to avoid 125 the said pinions, as clearly shown in Fig. 1.

Upon the inner side of the pendulum-bar A' is located a pawl, a, engaged with the ratchet-wheel B in such manner as to rotate the ratchet-wheel when the pendulum is moving downwardly, and upon the plate P is placed a second pawl or detent, a', also engaged with the ratchet-wheel and adapted to prevent backward movement of the latter. 130

The said pawl and detent may be constructed in any desired or well-known manner, those herein shown consisting of small pivoted clicks and separate springs a^2 a^3 , respectively secured to the arm A' and the plate P , and resting at their free ends upon the clicks in such manner as to hold them in contact with the ratchet-wheel. The teeth in the ratchet-wheel are preferably very small, between one and two hundred having been found a convenient number in watches of ordinary construction. The ratchet-wheel B is connected with the mainspring-arbor D by means of a train of intermediate gearing, herein shown as preferably composed of a pinion attached to the arbor of the ratchet-wheel B , a gear-wheel, e , and pinion upon an arbor, E , and a gear-wheel, d , upon the mainspring-arbor D . These several wheels and pinions will usually be so proportioned that the mainspring will be completely wound up by between three and four thousand vibrations of the pendulum, the parts in the particular watch shown being so proportioned that the watch will be wound for twenty-four hours by about two thousand vibrations of said pendulum.

As far as the construction of the pendulum and of the train of gears is concerned, the device herein shown is substantially similar to that illustrated in the patent previously granted to me, and hereinbefore referred to.

As an improved means for stopping the vibrations of the pendulum when the spring is completely wound, in order to prevent overwinding and consequent liability of breaking the spring or of irregularity in the action of the watch, which may be caused by the action of the spring upon the escape mechanism when the spring is too tightly wound, devices are shown in Figs. 2, 3, 4, 5, and 6, which are constructed as follows: F is the barrel of the watch, within which is located the mainspring G , and H is a movable plate or detent, which is provided with a notch, h , adapted to engage a stud or projection, I , upon the pendulum A , and which is pivoted upon the plate P adjacent to the dial by means of a stud or screw, h' , (shown in section in Figs. 2 and 3, in which the watch is shown with the said plate P removed,) said plate or detent being provided with a point or projection, h^2 , extending toward the mainspring-arbor D and adapted to engage the periphery of a serrated or finely toothed or notched wheel or disk, J , mounted to rotate freely upon said arbor D . K is a spring which is secured to the plate P , (a screw and stud connecting said spring with the said plate being shown in section in Figs. 2 and 7,) and is adapted to rest at its free end against a pin, h^3 , in the said detent H , in such manner as to tend to throw the part of the latter containing the notch h outwardly, or into position for engagement with the stud I . Upon the surface of the mainspring-barrel adjacent to the wheel J is mounted a pivoted pawl or detent, L , one end of which is adapted to engage a projection, tooth, or teeth upon the said wheel

J , and the opposite end of which is slotted, as indicated at l , and engaged with a projection, g , upon the spring G , near the outer end of the latter, said projection g being constructed to extend upwardly through a slot, f , in the barrel, and so arranged that when the spring is nearly wound up it will be drawn inwardly, and thereby move the said detent so as to release it from the wheel J . 75

An improved construction in the spring, whereby a considerable amount of inward movement of the stop g will take place before any considerable strain is put upon the portion of the spring adjacent to its outer end, is illustrated in the detail view, Fig. 5, in which the end of the spring G is shown as having secured to it, by rivets or otherwise, one end of a short piece of spring metal, G' , which extends backwardly along the outer surface of the spring, and the other end of which is attached to the barrel, the outer end of the spring thus being secured to the barrel through the medium of the said piece G' , instead of being directly attached to the barrel, as has heretofore been customary. The spring G , also, is provided near its end with a slot, g' , the effect of which is to weaken or render more flexible the part of the spring adjacent to its end. By thus weakening or rendering more flexible this part of the spring the latter is permitted to readily bend at the point mentioned when the spring is nearly wound, and thereby give a direct inward pull upon the end of the piece G' to which the spring is connected. The spring is usually so arranged that the inward movement mentioned will take place when the spring is within one-fourth of a turn of being completely wound. 100 The projection g , above referred to, is attached to the piece G' at its free end, or that which is connected with the spring, so that when the said piece G' is drawn inwardly or laterally by the tension of the spring the said projection 105 will be moved inwardly, for the purpose before mentioned. As a simple and convenient construction, the projection g is formed upon or integral with the piece G' , as shown. The part of the wheel J engaged by the pawl L 110 may be serrated, so as to be engaged by said pawl in the same manner as is the upper or outer portion thereof, which is engaged by the detent H . Instead of this construction, however, the said part of the wheel may be 115 provided with but a single tooth, j , for engaging the pawl, as shown in Fig. 6, or with two or other number of equally spaced teeth, if desired. 120

The particular object gained by the use of one or more than one tooth for engagement with the pawl L will appear in the following description of the operation of the device. When the watch is running, and either while it is being wound or when it is held immovable, so that the weight does not vibrate, the barrel F will turn in the usual manner and in the direction indicated by the arrow thereon in Figs. 2 and 3, and while so turning (the

spring being partially unwound and the pawl L therefore in engagement with the wheel J) the said wheel J will be carried around with the barrel and in the direction indicated by 5 the arrow 1 thereon. The point h^2 of the detent H being engaged with the serrated periphery of the wheel J, the rotation of said wheel in the direction last mentioned will obviously carry and hold the notch h of said detent away from the weight and against the action of the spring K, which, as before described, tends to cause engagement of the detent with the weight. The detent H will continue in the position described, the point 15 h^2 thereof slipping over the serrated edge of the wheel J, as the latter revolves, as long as the watch is running, and until it is completely wound up. When, however, by the continued action of the weight or pendulum the spring 20 is wound to a desired extent, the pawl L will be drawn inwardly by the action of the projection g at the end of the spring in the manner described, and said pawl thereby released from the wheel J. The said wheel now being 25 free to revolve, it will no longer operate to hold the detent against the action of the spring K, but will allow the notched end of said detent to be thrown forward by the spring K into position to engage the stud I upon the 30 pendulum, the said wheel being rotated backward or in the direction indicated by the arrow 2, Figs. 1 and 2, for a short distance in this movement of the detent. The rotary movement of the wheel J necessary to cause 35 engagement of the detent with the pendulum is relatively slight, and the point h^2 of the detent is made of such length and the notches of such depth that said point will fully enter the notch with which it is engaged when the 40 wheel is so turned that the point is in alignment with the pivotal axes of the wheel J and the detent, and will become disengaged and slip over the projections upon the wheel when the latter has been moved sufficiently to release the detent from the pendulum. The 45 detent H, when thrown outwardly in the manner described, will, unless the stud I is opposite the recess h , which is seldom liable to occur, rest at its outer edge against the stud until a subsequent movement of the weight brings the stud in opposition to the notch, when the spring will throw the end of the detent outwardly, so as to cause the engagement of the notch with the stud. After the pendulum or 55 weight is locked in the manner described the spring will begin to unwind and will continue to unwind until the projection g at the outer end thereof is permitted to move outwardly so as to carry the pawl L into engagement with the 60 wheel J, and the wheel has been carried by the said pawl through a distance (in the direction of the arrow 1) sufficient to release the detent from the stud I. Inasmuch, however, as the movement required for engaging the pawl with 65 the wheel J and the detent with the stud may be relatively slight, the engagement and disengagement of the detent and pendulum will,

when the wheel J is serrated, as shown in Figs. 2, 3, and 4, take place at comparatively short intervals—say about one-half hour apart— 70 when the person carrying the watch is moving continually, and in order to enable this time to be made longer, if desired, the part of the wheel J engaged by the pawl L may be provided with only one tooth, as indicated at 75 j , Fig. 6, or with several teeth placed at some distance apart, as indicated at j in dotted lines in said figure. By this construction it will be observed that when the pawl L is released from the wheel J and the said wheel allowed to rotate backwardly, under the action of the spring-detent engaged therewith, the pawl will become disengaged from the tooth engaged by it, which tooth will be carried under or past the pawl in the said backward 80 movement of the wheel, so that when the pawl is again advanced it will come into position in advance of the said tooth, and in the rotary movement of the pawl with the barrel said pawl will move without turning the wheel 85 J until the barrel has made a complete revolution and the pawl encounters the same tooth, in case one tooth is used, or the next tooth to the one previously engaged, in case several teeth are used. The number or distance apart 90 of the teeth j will be dependent upon the time it is desired the watch should run after it has been wound up and before winding again begins. It is not desirable that this time should be too long, otherwise the time 95 during which the watch will run without any motion tending to wind it will be objectionably shortened in case the watch has been completely wound and the pendulum locked, so as to prevent any winding by the movements of the wearer just previous to the beginning of the period of time during which it is allowed to remain quiescent. The length 100 of time during which the watch will run under these circumstances will obviously be less than the total time required for running down when the watch is fully wound by a period 105 equal to the length of time that it has previously run with the pendulum locked. If, on the other hand, the time during which the 110 watch may run before rewinding begins is very short, the winding device will be continually stopping and starting, so as to subject the stop mechanism to continuous action, 115 tending to wear it out and to produce irregularity in the action of the winding mechanism. The distance apart of the teeth, therefore, will be graduated to give a medium length of time 120 during which the watch may unwind, not usually less than half an hour nor more than 125 two hours.

In Figs. 7, 8, and 9 another form of stop device is shown having the same general features of construction before described, but in which a somewhat different mechanism upon the 130 barrel for holding the serrated wheel J from rotation is used.

As illustrated in the figures of the drawings last-mentioned, the means for holding

the said wheel J from rotation during the winding of the watch, instead of being actuated by a projection upon the outer end of the spring, as in the device before described, are 5 moved by a tooth, d , upon the mainspring-arbor D, which engages a notched disk, M, located upon the barrel F, adjacent to the said arbor, in such manner that the said disk will be turned through a distance of one tooth or 10 notch at each rotation of the arbor, in a manner well known in the construction of stop devices heretofore used for the prevention of overwinding of the mainspring in ordinary 15 watches. This notched disk M carries a projection upon its surface, which is so constructed and located in connection with a tooth or teeth, j' , upon the wheel J that the said projection upon the disk will be in position to engage a tooth upon the wheel, so as to hold 20 the latter from rotation during the winding of the watch, and will, when the watch is fully wound, be carried by the movement of the disk into position for disengagement from the said tooth, so as to allow the said wheel to rotate, and thereby release the detent in the same 25 manner as hereinafter set forth.

In the particular construction of the device above generally described, which is herein shown, the notched disk M is pivoted upon 30 the top plate of the barrel F by means of a dovetailed stud, f' , upon said barrel, the disk preferably having a relatively large central aperture with which the stud is engaged, and being split at one point, so it may be sprung 35 upon said stud in a familiar manner. The said disk M also is provided with a series of teeth, m , of which there are five shown, so as to form six notches, one of which is engaged by the tooth d upon the arbor D at each rotation 40 of the latter in winding, it being contemplated, in the watch shown, that the spring will be sufficiently wound by six rotations of the mainspring-arbor. Upon the upper surface of the said disk M is formed a segmental 45 rib or annular projection, M', which preferably extends through slightly more than half a circle, and is provided with an outer cylindric surface in position to engage the teeth j' upon the wheel J, said teeth being located 50 upon the lower part of the said wheel J, or that adjacent to the barrel, and adapted to pass over the upper surface of the disk M. The segmental projection M' is so located with 55 reference to the teeth m upon the disk that when the watch is unwound, and during the time that it is being wound up, said projection will be in position to engage one of the teeth j' , and to retain the wheel J in position to hold the detent H free from engagement 60 with the pendulum. The ends m' and m'' of the said segmental projection M', also, are so placed that when, in the rotation of the barrel, the tooth B' upon the arbor engages the last tooth of the series m , and the spring is 65 sufficiently wound, the tooth j' engaged with the said projection will be released from the end m' thereof and allowed to move inwardly

past said projection, and thereby allow the wheel J to freely rotate and the detent to be thrown outwardly by the spring K.

The position of the parts immediately after the tooth engaged with the projection has been released therefrom is illustrated in Fig. 8. The said projection may obviously extend through any part of a circle necessary in order to hold the wheel J from rotation during a desired time, depending upon the distance apart of the teeth m and the number of times it is necessary to turn the arbor to sufficiently wind the watch.

As herein shown and preferably constructed, the ends of the segmental projection or rib M' are so arranged that when the end m' engaged with a tooth j' is in position to release said tooth the opposite end, m'' , will be at the same distance from the center of the spring-arbor as the said end m' , so that when the watch begins to run down after the pendulum has been locked, in the manner above described, said projection M' in the bodily movement of the disk M with the barrel will pass without striking the tooth which has just been disengaged therefrom. It will be understood, of course, that as soon as such unwinding or bodily movement of the disk with the barrel begins the said disk and the rib M' will be turned backwardly, or in the direction of the arrow in Fig. 8, so as to bring the end m' of the angular projection into position to engage the tooth following that which was previously engaged therewith, or, in case there is only one tooth, to re-engage the same tooth after a complete rotation of the barrel.

It will be readily seen that the time during which the watch will run down after the pendulum has been stopped may be varied by changing the number of teeth j' upon the wheel J or their distance apart in the same manner as before described in connection with the tooth or teeth j shown in Figs. 2, 3, and 6.

In the construction of the devices above described, herein shown, and illustrated more clearly in Fig. 9, the tooth d' is formed upon a collar, d'' , attached to a sleeve, d'' , which is fitted upon the squared portion d^3 of the arbor D, upon which the gear d is also placed, the wheel J being fitted to rotate upon the said sleeve d'' .

In the particular form of the detent H shown in Figs. 2, 3, 7, and 8 the edge thereof adjacent to the pendulum is so formed that the stud I is caused to pass over a gradual incline in order to reach the notch in passing to the notch from either side of the latter. It will also be observed that, as shown in the said figures, the location of the pivot h' of the said detent is such that when the said detent is fully thrown out the point h'' thereof, which is engaged with the wheel J, will be carried to or slightly beyond or above a straight line passing through the pivotal axis of the detent and the axis of rotation of the wheel, so that the said detent will be locked outwardly, and the pendulum cannot be released, except by

the said wheel J being rotated. The advantage of this construction is, that the pendulum is thereby held positively and cannot be unlocked by the yielding of the spring K. The 5 notch h and the stud I are also preferably constructed, Figs. 2, 3, 7, and 8, with their side edges perpendicular to a line drawn from the center of the pivot h' through the said notch, so that the pressure of the stud 10 upon the sides of the notch will be directly toward the pivotal axis of the detent, and will therefore have no tendency to rotate the latter in either direction.

In Fig. 10 a form of the stop device is shown 15 embodying the same general principles of construction, so far as the use of a spring to throw the detent into engagement with a notch in the pendulum is concerned, but in which devices generally similar to those shown in my said 20 prior patent, No. 293,691, are used to move the spring bodily at a desired time, in order to cause the engagement of the detent and pendulum. This device comprises, essentially, a notched disk, M, pivoted upon the barrel and actuated 25 from a tooth upon the mainspring arbor, a wheel, J, loosely mounted upon the said arbor and connected with the barrel, so as to rotate with the latter, by means of a spring, j², said wheel J also being provided with a finger, j³, 30 adapted to engage a tooth or projection, m³, upon the disk M, and a pivoted plate or detent, H, provided with a point or projection, h⁴, engaged with the serrated wheel J, and with a part or projection, h⁵, adapted to engage a notch, I', in 35 the pendulum, said projection h⁵ in this case being made in the form of a spring. In the operation of this device the disk M will be turned one notch by the tooth upon the arbor at each 40 revolution of the barrel, and when the spring is wound to a desired extent the tooth m³ upon the said disk will encounter the finger j³, thereby rotating the wheel J backwardly against the resistance of the spring j², and carrying the plate H in position for engagement of the projection h⁵ with the recess of the 45 pendulum. The spring h⁴ is made of such strength that it will yield backwardly when the projection h⁵ is pressed against the pendulum, until, by the movement of the latter, 50 the notch I' is brought into position for engagement with the said projection. The said projection h⁵ will obviously enter the recess I' a distance dependent upon the extent of the movement of the pendulum tending to wind 55 the watch after the said projection comes in contact with the pendulum and before the said recess is brought opposite the projection. This movement may in some cases be so slight as to make the time during which the spring 60 must unwind in order to release the pendulum objectionably short, and for this reason the use of the devices shown in Figs. 3, 4, 7, and 8 is preferred in practice.

It will be understood that two or more 65 notches may be provided in the detent when the construction herein shown is used, or two or more notches may be made in the pendulum

when a projection is used upon the detent, so that a less extent of movement in the pendulum after the detent is released and thrown outwardly by the spring is required to cause the positive engagement between the detent and pendulum than in the construction herein shown. Inasmuch, however, as the movement of the pendulum is comparatively slight, 70 and the said pendulum will practically in all cases come into position for engagement with the notch at its first vibration, the use of more than one notch or projection will usually be unnecessary. It is obvious, also, that instead 75 of the spring herein shown for actuating the detent an equivalent weight may be used; but, for evident reasons, a spring is preferred for this purpose.

In the patent above referred to as having 80 been granted to me springs are shown attached to the watch-plates in position to encounter the upper and lower ends of the pendulum, so as to take up the impetus of the weight, and which also tend to throw the weight backward 85 in its oscillatory movement. Another form of spring device for the same purpose is herein shown, which embodies the same principles of operation. In this case a single spring, N, Fig. 1, is shown as secured to the plate P adjacent to the dial and arranged to extend inwardly over the pendulum in position to be encountered by pins n upon the said pendulum, said pins, as herein shown, being secured in a part of the arm A'. In the vibratory 90 movement of the weight the spring N will obviously alternately strike the pins n with the same result as is obtained by the use of the two separate springs shown in the said prior 95 patent.

In taking apart a self-winding watch of the character above described, for cleaning, repairs, or other purposes, considerable difficulty has heretofore been experienced in unwinding the mainspring, for the reason that 100 the ratchet-wheel B, which is geared with the mainspring-arbor, is engaged both by the pawl a upon the pendulum-arm, and also by the detent a' upon the plate, it being practically impossible for one person to at once hold 105 both the pawl and detent out of engagement with the ratchet-wheel, and at the same time to hold the spring as it unwinds. Injury to the watch is also liable to occur in attempting to unwind it in this manner, for the reason 110 that unless both the pawl and detent are positively held clear from the ratchet their ends are liable to strike the latter in its backward movement, and so as to cause injury both to the pawl and detent and to the ratchet-wheel. 115

In order to provide a convenient means for holding both the pawl and detent out of engagement with the ratchet-wheel for the purpose above stated, means are herein provided as follows: The ends of the pawl and ratchet 120 which are engaged with the ratchet-wheel are placed at such distance apart that when the detent is thrown outwardly or disengaged from the ratchet, and when the pendulum is at the 125

upper limit of its movement, as is shown, for instance, in Fig. 1, the free end of the pawl upon the pendulum-arm will be engaged by the free end of the detent in such manner that the said pawl will also be held out of engagement with the ratchet.

In order to enable the detent to be positively and readily moved so as to disengage it and the pawl, the plate P, to which the detent is attached, is provided with an aperture, p, at a point adjacent to the said detent, and in said aperture is located a pin, o, in position to engage the side of the detent adjacent to the ratchet-wheel, said pin o being attached at the opposite or inner side of the plate P, Figs. 11 and 12, to a rod or plate, O, which is held by a spring-support secured to the said plate P in such manner that the pin o will be held normally free from contact with the detent and in position to allow the latter to engage the ratchet. The said plate O is arranged in such position that it may be reached by a pin or other slender instrument from a point exterior to the plates of the watch, so that it may be moved in a direction to carry the pin toward the detent, and to cause the said pin to throw the free end of the said detent out of engagement with the ratchet.

In the construction of the parts herein shown, and illustrated more clearly in detail, Figs. 11 and 12, the plate O is arranged to extend from the pin o outwardly toward the edge of the plate, and is attached to a transversely-arranged spring, O', secured to the under or inner side of the plate P. The said spring is herein shown as being made in one piece with the plate O.

In the particular watch herein illustrated the plate O is so located that its outer end is opposite one of the posts P² connecting the plates P and P' of the watch, and the said post is provided with a transverse aperture, p', through which the pin may be inserted for pressing the plate O inwardly, and thereby moving the detent, as above described.

It will be observed that the effect of pressing inwardly upon the outer end of the bar or plate O, as described, is not only to thrust the said bar inwardly toward the center of the watch, but also, on account of the attachment of the plate to the spring O', located at right angles thereto, to cause the inner end of said plate which carries the pin o to move laterally, so as to move the pin toward the detent in a direction transverse thereto.

By the use of the releasing device above described the spring may obviously be unwound in a watch in which the self-winding device is at the side of the watch adjacent to the dial without removing the latter.

It is obvious that a releasing pin, o, and a spring-plate, O, supporting it, can be so arranged that it may be moved by an instrument inserted through a suitable aperture in the plate P', or that remote from the dial, without the necessity of taking the works from the case for this purpose. The arrangement

herein illustrated is preferred, however, for the reason that by its use the detent and pawl are much less likely to be released by accidentally moving the pin o, or by the plate O being intentionally disturbed by a person ignorant of its purpose.

The essential feature of novelty in that part of my invention which relates to the stop mechanism for locking the pendulum consists in the use, in connection with a spring-actuated detent adapted to normally engage the pendulum, of mechanism constructed to hold said detent out of engagement with the pendulum while the watch is being wound, and to release said detent so as to allow it to engage the pendulum when the watch is fully wound. In carrying out this feature of the invention it is obviously not essential that the spring-detent should be constructed as herein shown, and any movable part adapted to engage a projection upon or a notch in the pendulum, or to otherwise engage the latter so as to hold it from movement, may be used. The spring by which the detent is actuated may also be separated from or made in one piece with the detent, or otherwise applied so as to properly move the detent, without departure from my invention. Other devices than those herein illustrated may also be used for holding the detent from engagement with the pendulum, and for releasing the said detent at a desired time, with the same novel results as herein set forth. I desire, therefore, to claim, broadly, all devices for the purpose above mentioned operating upon the general principles herein set forth, as well as the particular devices herein illustrated as a practical embodiment of my invention.

A device for releasing the detent and pawl from the ratchet engaged by them in unwinding the watch, such as is herein shown, I consider to be essentially novel with me, and said device is, therefore, broadly claimed herein without restriction to the particular form thereof which is illustrated herein.

I claim as my invention—

1. In a self-winding watch, the combination, with a vibrating pendulum, of a spring-actuated detent adapted to normally engage said pendulum, means for holding said detent out of engagement with the pendulum against the action of the spring, and means actuated by part of the watch mechanism which is moved in winding, constructed to release the detent, so as to permit its prompt engagement with the pendulum when the watch is wound to a desired extent, substantially as described.

2. In a self-winding watch, the combination, with a vibrating pendulum, of a spring-actuated detent adapted to normally engage said pendulum, means for holding said detent out of engagement with the pendulum against the action of the spring, and means actuated by a part of the watch mechanism which is moved in winding, constructed to release the detent, so as to permit its prompt engagement with the pendulum when the watch is wound to a

desired extent, and means constructed to disengage the said detent from the pendulum at the end of a desired time after such engagement, substantially as described.

5. 3. In a self-winding watch, the combination, with a vibrating pendulum, of a spring-actuated detent adapted to normally engage the pendulum, a notched or serrated wheel, as J, engaged with the detent, means connecting the said wheel with the mainspring-barrel, whereby the wheel is caused to rotate with the barrel in a direction to hold the detent out of engagement with the pendulum, and means operated by a part of the watch mechanism 15 which is moved in winding, constructed to disengage said wheel from the barrel when the watch is wound to a desired extent, whereby said detent is caused to promptly engage the pendulum, substantially as and for the purpose set forth.

4. In a self-winding watch, the combination, with a vibrating pendulum, of a spring-actuated detent adapted to normally engage the pendulum, a notched or serrated wheel, as J, mounted concentrically with the mainspring-barrel and engaged with the detent, a movable part or projection upon the mainspring-barrel adapted to engage a tooth or projection upon said wheel J, and means operated by a part of 30 the mechanism which is moved in winding, constructed to move said part or projection when the spring is wound to a desired extent, so as to release the wheel and permit the prompt engagement of the detent with the pendulum, substantially as and for the purpose set forth.

5. In a self-winding watch, the combination, with the mainspring, mainspring arbor and barrel, and a vibrating pendulum, of a spring-actuated detent adapted to engage the pendulum, a notched or serrated wheel, J, mounted to rotate freely concentrically with the mainspring-arbor and engaged with the detent, a pawl pivoted upon the mainspring-barrel and 45 engaged with the wheel J, and a projection, g, upon the mainspring engaged with the said pawl, substantially as and for the purpose set forth.

6. In a self-winding watch, the combination, 50 with the mainspring, a mainspring arbor and barrel, and a vibrating pendulum, of a spring-actuated detent adapted to normally engage the pendulum, a piece, G', of spring metal attached to the end of the mainspring and connecting the latter with the barrel, a projection, g, upon the mainspring, means engaged with the detent, constructed to hold the latter free from engagement with the pendulum, and means actuated by the inward movement of 55 the projection g when the spring is fully wound, constructed to release the said detent, so as to permit its engagement with the pendulum, substantially as described.

7. In a self-winding watch, the combination, with the mainspring, mainspring arbor and 65 barrel, and a vibrating pendulum, of a spring-actuated detent adapted to engage the pendulum, a notched or serrated wheel, J, mounted concentrically with the mainspring-arbor and engaged with the detent, a pawl, L, pivoted 70 upon the barrel and engaged with the said wheel, and a piece, G', connecting the end of the mainspring with the barrel and provided with a projection, g, engaged with the said pawl, substantially as and for the purpose set 75 forth.

8. In a self-winding watch, the combination of a mainspring provided with a slot, g', near its outer end, a mainspring arbor and barrel, a vibrating pendulum, a spring-actuated detent adapted to engage the pendulum, a piece, G', of spring metal attached to the end of the mainspring and connecting the latter with the barrel, a projection, g, upon the mainspring, means constructed to hold the detent free from 80 engagement with the pendulum, and means actuated by the inward movement of the projection g when the spring is fully wound, constructed to release the said detent, so as to permit its engagement with the pendulum, substantially 90 as described.

9. In a self-winding watch, the combination, with the vibrating pendulum, of a single spring, N, and stops n n upon the watch-plate and pendulum, substantially as and for the purpose set forth.

10. In a winding mechanism comprising a vibrating pendulum and a pendulum-arm, a ratchet-wheel, and a pawl upon the arm and a detent upon the watch-plate engaged with 100 the said ratchet-wheel, said detent being located in such position that when released from the ratchet-wheel it will be encountered by the pawl, so as to free the latter from the ratchet-wheel in the upward movement of the pendulum, means engaged with the detent, whereby 105 the latter may be moved from the outside of the plates, substantially as and for the purpose set forth.

11. In a winding mechanism comprising a 110 vibrating pendulum and pendulum-arm, a ratchet-wheel, a pawl upon the arm, a detent upon the watch-plate engaged with the said ratchet-wheel, and a spring-supported plate, O, provided with a pin, o, adapted to engage the 115 said detent, substantially as and for the purpose set forth.

In testimony that I claim the foregoing as my own I affix my signature in presence of two witnesses.

HERMANN VON DER HEYDT.
